UNITED STATES PATENT OFFICE.

SANDFORD C. COX OF CHICAGO, ILLINOIS, ASSIGNOR, BY MESNE ASSIGNMENTS, TO COX
MULTI-MAILER COMPANY, OF AUGUSTA, MAINE, A CORPORATION OF MAINE.

TOWN-MARKER FOR ADDRESSING-MACHINES.

No. 901,954.

Specification of Letters Patent.

Patented Oct. 27, 1908.

Application filed May 29, 1905. Serial No. 262,723.

To all whom it may concern:

Be it known that I, SANDFORD C. COX, a citizen of the United States, residing at Chicago, in the county of Cook and State of Illinois, have invented certain new and useful Improvements in Town-Markers for Addressing-Machines, of which the following is a full, clear, and exact specification.

My invention relates to means for automatically separating into definite batches the various papers or other like articles addressed to or intended for subscribers in certain towns or localities, and for the want of a more generic term it is herein designated as a town marker for addressing machines, but it will nevertheless be understood that it is applicable to other uses and in fact all purposes where it is desired to automatically separate or distinguish one batch of papers or other articles from another after the same have been individually addressed or otherwise treated.

The generic invention forms the subject of my pending application Serial No. 65806, filed June 24th, 1901, upon which the present invention is designed as an improvement, and my present invention has for its object to provide improved means adapted to place upon the papers an imprint or other distinguishing device by which the various batches may be distinguished one from another.

The invention consists in certain features of novelty in the construction, combination and arrangement of parts by which I accomplish the said objects and certain subsidiary objects and which will now be fully described with reference to the accompanying drawings and more particularly pointed out in the claims.

In the said drawings—Figure 1 is a side elevation of a part of an addressing machine embodying my improvements. Fig. 2 is a plan view thereof. Fig. 3 is a detail side elevation of a part of the addressing means. Fig. 4 is an enlarged detail plan view of the marker. Fig. 5 is a detail cross section on the line 5, 5 Fig. 4. Fig. 6 is a detail view of one of the notched slugs. Fig. 7 is a similar view of one of the unnotched slugs. Fig. 8 is an enlarged detail side elevation of the marking mechanism with associated parts in section and showing the marker elevated. Fig. 9 is a similar view showing the marker depressed or in action. Fig. 10 is an en-

larged view of the marker showing the manner in which it engages the edge of the paper. Fig. 11 is a side elevation of a part of the slug drum or wheel and the marker actuating arms, and Fig. 12 is an enlarged side elevation of the paper stops and operating cam.

1 is the slug wheel or drum which is provided with pockets or recesses 2 in which the slugs 3, 4 lodge and are held by suitable clamps 5, while the papers 6 pass over the slugs and are stamped or printed by a stamper 7, which is forced downwardly against the paper at the proper time and thereby impresses the paper against the top slug for printing the address thereon, all as shown and described in my aforesaid application. Cut into the edges of the slug pockets concentrically with the drum or wheel 1 are notches or grooves 9 in which engages a shoe 10 mounted upon a lever or arm 11 pivoted on any suitable support at 12 at one end and having its other end connected to a sleeve 13 by means of a lug 14 and adjustable connection, preferably comprising two rods 15, 16 pivoted to the lug 14 and arm 11 respectively and screw threaded in a turn buckle 17 whereby the position of the sleeve 13 with relation to the shoe 10 may be varied at will.

The sleeve 13 is loosely mounted upon a shaft 18, or any other suitable support, and carries a clutch member 19 rigidly secured thereto opposite a companion clutch member 20 which may also be loosely mounted upon the shaft 18 and which is provided with an arm 21 connected in any suitable way to a driving shaft 22. The means shown in the drawing consists of a shaft 23 connected by bevel gears 24 to the shaft 22 and having a cam 25 which engages a stud 26 on an arm 27 rigidly secured to the shaft 18 and also to a rocker arm 28 through the medium of the shaft and to which shaft the rocker arm 28 is pinned or otherwise secured and has a forked end engaging a pin 29 on the short arm 30 of a lever pivoted on a stud 31 and having its long arm 32 provided with a pin 33 which engages in a fork 34 in the free end of arm 21 and consequently when the shaft 22 revolves, causing the cam 25 to oscillate the arm 27 and thereby rock the shaft 18, the clutch member 20 will be accordingly rocked or oscillated, and should the member 19 at that time be in engagement with the member 20, the sleeve 13 will be accordingly

rocked and a marker arm 35 secured to the sleeve will be depressed, but at all other times the arm will remain inactive. As better shown in Fig. 5 the shoe 10 is arranged 5 in line with the concentric series of notches 9 in the slug drum or wheel and is therefore pressed outwardly by the slugs 4 in the pockets 2 and prevents the clutch member from engaging the member 20, but some of 10 the slugs 3, Fig. 6, are provided with notches 3* in their ends or are otherwise proportioned differently from the slugs 4 so that when the notches 3* reach the shoe 10, a spring 36 arranged on the shaft 18 and 15 bearing against the end of the sleeve 13 will instantly act to push the clutch member 19 into engagement with its companion member and marker arm 35 will be thereby depressed, but as soon as the shoe 10 is engaged by one of the slugs 4 the clutch member 19 will be withdrawn.

The notched slugs 3 may be the ones which bear either the last or first address of all papers going to each town or locality. 25 and as a consequence as soon as the last paper is addressed the marker 35 will be depressed and an impression device or roller 37 mounted in the arm 35 will be caused to engage the edge of the paper 6 in the manner shown in Fig. 10, the impression device 37 receiving its ink from any suitable ink roller 38 also mounted in arm 35 and provided with a racket 39 adapted to be engaged by a pawl 40 mounted on a standard 35 41 upon which may also be arranged a spring 42 for lifting the impression wheel or roller 37 out of engagement.

Arranged immediately below the paper is a support 43 for sustaining it while the impression of the roller 37 is being made, and 40 immediately below the roller 37 in the support 43 is formed a countersink 44 into which the roller 37 depresses the edge of the paper, as shown in Fig. 10 just as the edge 45 projects slightly beyond the edge of the countersink. This enables the roller to make its impression on the edge of the fold rather than on the face of the sheet so that when the papers are stacked the mark on the edge 50 of the fold will be visible, it being understood that this mark is produced on the margin of the paper.

Before the stamper 7 depresses the paper against the slug the paper is squared up and 55 momentarily stopped and it is at this time that the marker 37 produces its impression, the paper being stopped in such a position that its edge will slightly project beyond the edge of the countersink 44. The means for 60 accomplishing this comprises a number of arms 45 having stops 46 mounted thereon and adapted to descend across the line of movement of the papers which are carried between conveying tapes 47, 48 which serve 65 to conduct them over the slugs in the slug

drum or wheel 1 and to carry them between guard plates 49, 50, which are provided with slots 51 for the admission of the stops 46. The arms 45 are mounted upon a rocker shaft 52 which is oscillated in any 70 suitable manner just before each impression occurs, as for example by an arm 53 mounted on the shaft 52 and engaging a cam 54 on the end of driving shaft 22.

The slug wheel or drum 1 is driven in 75 unison with the shaft 23 by any suitable means, such as a worm 55 mounted upon shaft 23 and engaging a worm wheel 56 secured to shaft 57 upon which the drum 1 is mounted whereby the drum will be rotated 80 at such a speed that one of the slugs or slug pockets will be brought under the stamper 7 each time the stamper shaft 18 is oscillated.

The papers are delivered by the tapes 47, 48 upon a traveling conveyer comprising 85 tapes 58 and rolls 59, 60 over which the tapes 58 travel and which rolls are mounted on any suitable frame 61. The roll 60 is connected by sprockets 62, 63 and a chain 64 with the shaft 57 whereby the tapes 58 90 will be caused to travel in a direction away from the machine and conduct the papers away as rapidly as they are deposited, the papers being thus deposited one upon another with the edge of the bottom one 95 slightly in advance of the top one so that the marks produced by the marker 37 will be visible as the papers lie upon the table or conveyer.

In order that the table or conveyer may 100 be adjusted at the outer end to suit the elevation of any ordinary table or support that may be placed contiguous thereto for receiving the papers therefrom, the frame 61 is pivoted on the shaft 65 of the roll 60 and 105 its outer end is supported by a rod 66 and a sleeve 67, which latter is pivoted at 68 to the frame of the machine and into which a threaded end 69 of the rod is inserted and carries a nut 70 resting against the end of 110 the sleeve so that the rod may be adjusted as desired.

Having thus described my invention what I claim as new therein and desire to secure by Letters Patent, is:

1. In a device for the purpose described the combination of individual disconnected and independent addressing devices, means for causing the same to travel to and from a printing position, means for placing a distinguishing mark upon the papers, conveying means for conducting the papers past said marker, means for holding the marker inactive while some of the papers pass it, and means operatively related to some of said addressing devices for rendering the marker active while other papers pass it. 120

2. In a device for the purpose described the combination of individual addressing devices, means for causing the same to travel 125

to and from a printing position, an ink impression device for marking the papers, conveying means for conducting folded papers and presenting the folded edges thereof to 5 said ink impression device, means for holding the impression device inactive while some of the papers pass it, and means operatively related to some of said addressing devices for pressing the impression device against 10 the folded edge of the paper contiguous thereto.

3. In a device for the purpose described the combination of individual devices for addressing folded papers, and means operatively related to some of said devices for placing an impression against the folded edge of some of the papers. 15

4. In a device for the purpose described the combination of a paper addressing 20 means, a table comprising a pivoted traveling conveyer for receiving the addressed papers, means for adjusting said conveyer upon its pivot, and means for projecting the papers upon the conveyer.

5. In a device for the purpose described the combination of means for addressing the papers, means for conducting the papers to the addressing means, means arranged in line of movement of the papers for squaring 30 the papers up preparatory to being addressed, a marker for engaging the papers and producing a distinguishing mark thereon, means for holding said marker inactive while some of the papers pass it, means for rendering the marker active when others of the papers pass it, operatively related to the said means for squaring the papers up whereby it will act in time therewith. 35

6. In a device for the purpose described, the combination of a support for the papers 40 to be marked, having a depression, a marking device movable towards and from said depression for pressing the edge of the paper thereinto as it rests upon said support, means for conducting the papers to said support, 45 individual addressing devices for producing an imprint upon the papers, differently proportioned with respect to each other, and means co-operatively related to said addressing devices of a certain proportion for 50 actuating said marking device.

7. In a device for the purpose described, the combination of means for placing an imprint or address upon papers, embodying a rotating slug carrying wheel adapted to carry 55 a plurality of printing slugs, a plurality of such slugs in said wheel differently proportioned with respect to each other, means for placing a distinguishing mark upon the papers printed by the slugs of a certain proportion, embodying a marking member adapted to engage the paper to be marked, an actuating member co-operatively related to the slugs in the wheel and having co-operative relation to the said marking member. 60

8. In an addressing machine the combination with a means for feeding the articles to be addressed and printing the addresses upon one side thereof, of mechanism actuated by the first mentioned means for affixing a distinguishing mark to the other side of the article to be addressed. 70
